[57] **CLAIM**

The ornamental design for a border and stitching thereon for a backpack, as shown and described.

DESCRIPTION

FIG. 1 is a front elevational view of a border and stitching thereon for a backpack embodying my new stitching design for a backpack.

The broken line showing of a backpack is for illustrative purpose only and forms no part of the claimed design.

The side, back, top and bottom views of the border and stitching thereon for a backpack are plain and unornamented.
